BY F. M. WRIGHT,

UNITED STATES PATENT OFFICE.

JAMES R. ELDER, OF OAKLAND, CALIFORNIA.

COLLAPSIBLE BED.

1,372,659.

Specification of Letters Patent. Patented Mar. 22, 1921.

Application filed September 27, 1917. Serial No. 193,409.

To all whom it may concern:

Be it known that I, JAMES R. ELDER, a citizen of the United States, residing at Oakland, in the county of Alameda and 5 State of California, have invented new and useful Improvements in Collapsible Beds, of which the following is a specification.

This invention relates to improvements in beds having legs and head and foot pieces 10 which can be collapsed or folded to enable the bed to be rolled into a receptacle of small height or beneath another bed. The object of the invention is to provide a bed of this character having movable parts so 15 arranged that the bed will be compact and will not interfere with the bed clothes.

In the accompanying drawing, Figure 1 is a perspective view of the bed extended for use; Fig. 2 is a similar view of the same 20 collapsed; Fig. 3 is a cross sectional view of a portion of the bed on the line 3—3 of Fig. 4; Fig. 4 is a longitudinal section of said portion; Fig. 5 is a detail sectional view.

25 Referring to the drawing, 1 indicates side rails of the bed which are in the form of angle-irons with their vertical members 2 depending from the outer sides of the horizontal members 3, and connected at the ends 30 by end rails 4 which are also in the form of angle-irons having their vertical members extending upward from the outer edges of the horizontal members, and to these latter is attached the fabric or other springs (not 35 shown) for supporting the bed mattress.

40 Adjacent to their ends the horizontal members 3 of the angle-irons are slotted, as shown at 6, and through said slots extend the angular end members 7 of end pieces 8 forming respectively the head piece and foot 45 piece of the bed. Said angular members 7 are pivoted between the vertical members 2 of the side rails and angular brackets 9 fastened to the horizontal members 3 of the side 50 rails, and to the lower ends of said angular members are pivotally connected by means of the ends of rods 11, the upper ends of legs 12, the lower ends of said legs being mounted 55 upon rollers or casters 13. Said rods 11 extend in a transverse direction relative to the bed, and their lower ends extend through, and are connected to, the lower ends of the legs 12 on the side of the bed opposite to the angular members 7 to which 60 their upper ends are connected. While the main portions of the rods extend obliquely

65 downward transversely to the bed, their upper ends extend horizontally, as shown in Fig. 5, and said upper ends are threaded, as shown at 14, and on to them are screwed 70 socket pieces 16 which extend through the angular members 7 and legs 12 and form pivots therefor, nuts 17 being screwed upon said threaded portions 14 of the rods against the ends of said socket pieces to hold the 75 adjacent ends of the parts 7 and 12 in place. To collapse the bed the end pieces are swung upon their pivots, so that the main portions of said end pieces extend horizontally toward each other parallel with the bed frame 80 and holding the bed clothes between themselves and the bed frame. By this movement the lower ends of the angular pieces are swung upwardly into close proximity to the side rails, and by the same movement the 85 legs 12 are also swung into a nearly horizontal position in close proximity to the side rails, for the reason that said legs 12 are tied to said side rails by tie rods 18, pivotally connected at their ends, as shown at 19, 90 21, to mediate portions of the legs and to the side rails respectively. Spring latches 15 are secured to the inner sides of the end members 32 of the end pieces and engage the horizontal members of the end rails to hold 95 the end pieces in their extended positions. While four such spring latches are herein shown, any one of these latches alone will be operative for this purpose. Coiled springs 22 are attached at their ends respectively to the side rails and angular portions 100 by means of eyes 23, 24, in said side rails and angular portions and oppose a movement of the end pieces from an extended to a collapsed position and assist in moving the 105 end pieces to their extended position when required and therefore in raising the bed from its lower position to its position ready for use. The angular members of the head piece and foot piece respectively are operatively connected with each other, so that both can only move at the same time, by means of rods 26, the outer ends of which are pivotally connected to said angular members beneath the pivots of the latter, 110 while their inner ends are pivotally connected to rocking arms 27, which are pivoted to angle-irons 30 attached to the horizontal members of the side rails.

When the end pieces are collapsed and the legs are raised into close proximity to the side rails, the side rails are supported by

means of rollers 28 mounted in short forked legs 29 depending from said side rails.

Upon the side rails at their ends and near their inner edges are secured guard plates 31 which serve to protect the bed clothes from being pinched and torn by the end pieces when moving from their extended to their collapsed position, or conversely.

The provision of the slots 6 in the horizontal members of the side rails permits the end pieces to be moved about their pivots without the necessity of any projections outside the side rails, and without interfering with the bed clothes.

15 I claim:

1. In a collapsible bed, the combination of a bed frame having side rails, end pieces having angular members extending from the ends of the bed longitudinally toward each other and pivoted to said side rails, means for holding the end pieces in an upright position, legs pivotally secured to the lower portions of said angular members, rollers upon which the lower ends of the legs are mounted, tie rods pivotally connected to the side rails and to said legs at points intermediate between their pivots and said rollers, rods each connected in its outer end to the part of an angular member beneath its pivot and a rocking arm pivoted upon the adjacent side rail and connected at its ends between the ends of said rods.

2. In a collapsible bed, the combination of a bed frame having side rails consisting of angle-irons with horizontal members having therein longitudinally extending slots, end

pieces having angular members extending from the ends of the bed longitudinally toward each other and extending through said slots and pivoted to said side rails, guard plates secured on the horizontal members of said side rails on the inner sides of said angular members and slots, legs pivotally secured to the lower portions of said angular members, rollers upon which the lower ends of the legs are mounted, and tie rods pivotally connected to the side rails and to said legs at points intermediate between their pivots and said rollers.

3. In a collapsible bed, the combination of a bed frame having side rails consisting of angle-irons with horizontal members having therein longitudinally extending slots, end pieces having angular members extending from the ends of the bed longitudinally toward each other and extending through said slots and pivoted to said side rails, rods each connected at its outer end to the part of an angular member beneath its pivot and a rocking arm pivoted upon the adjacent side rail and connected at its ends between the ends of said rods, latches secured to said end pieces and engaging the bed frame to hold the end pieces in their extended position, legs pivotally secured to the lower portions of said angular members, rollers upon which the lower ends of the legs are mounted, and tie rods pivotally connected to the rails of the bed and to said legs at points intermediate between their pivots and said rollers.

JAMES R. ELDER.
